UNITED STATES PATENT OFFICE.

CHARLES P. WATSON, OF PHILADELPHIA, PENNSYLVANIA.

FIREARM-PROJECTILE.

1,322,662.

Specification of Letters Patent. Patented Nov. 25, 1919.

Application filed January 19, 1916. Serial No. 72,974.

To all whom it may concern:

Be it known that I, CHARLES P. WATSON, a citizen of the United States, residing at Philadelphia, in the county of Philadelphia 5 and State of Pennsylvania, have invented certain new and useful Improvements in Firearm-Projectiles, of which the following is a specification.

My invention relates to improvements in 10 projectiles for fire arms some of which are adapted to be used in connection with projectiles of many different sizes and forms, and have for their object to improve the flight of the projectile, while others are more 15 restricted in their application and are particularly adapted for use in connection with mushroom bullets such as are used with sporting rifles in the killing of game, these having especially for their object to render 20 the bullet more destructive in its action, as will be hereinafter pointed out.

In the accompanying drawings—

Figure 1 is a longitudinal sectional view 25 of a bullet for a sporting rifle made according to my invention, the core constituting the point of the bullet being represented in elevation.

Fig. 2 is an elevation of the bullet.

Fig. 3 is a transverse sectional view taken 30 on the line III—III of Fig. 1.

Referring to these drawings, 2 indicates the body of the bullet, which is formed of lead or other suitable relatively soft metal. This is inclosed by a jacket 3 of harder 35 metal, such as brass. The body 2 and its jacket are cylindrical or taper slightly toward their forward ends. In the body 2 is formed a central longitudinal cavity 4 to receive the tapering shank or stem 5 of a 40 core of hard metal, such as steel, brass or copper, the head or point 6 of which constitutes the nose or pointed end of the bullet. Between the exposed point 6 and the stem 5 of the core is a tapering shoulder 8 against 45 which bears the forward end of the body 2. Substantially the entire surface of the exposed part or head 6 of the core is pitted or formed with shallow empty recesses, as indicated at 9, the recesses being preferably 50 round in outline and arranged close to each other but not in contact, though they might be of other shape and arrangement from that shown. A bullet such as described has all of its exposed parts of hard metal, and 55 hence is not liable to be deformed through such handling, whether careless or other-

wise, as it may receive preparatory to being expelled from the rifle upon the discharge thereof.

The pitting or recessing of the forward 60 tapering end of a projectile, as described, improves its flight, causing it to have a flatter trajectory and to travel with greater accuracy than does a projectile the nose of which is smooth exteriorly. I believe that 65 this is because the pits or recesses 9 become filled with air which is more or less pocketed or retained, the result being that as the projectile passes through the atmosphere 70 there is friction of air against air to a considerable extent over the penetrating surface of the bullet, instead of metal against air only.

Upon the firing of the gun the steel core 75 will very slightly set back into and expand the body of the bullet, due to the tapering form of the shank of the core, and to the fact that the mass of the core relative to the entire mass of the bullet is sufficient to permit a set-back movement of the 80 core relative to the body, thus forcing the jacket 3 into the rifling of the gun, with the result that the gases of propulsion are retained behind the bullet and their full force made available upon the bullet, and 85 erosion, due to the leakage of gases past the bullet, is reduced to a minimum. The set back of the core is only slight, scarcely noticeable to the eye, but is sufficient to cause the bullet to take the rifling in a very superior manner.

Upon the bullet striking the objective, such as the body of an animal, it readily penetrates, due to the sharp nose or point 90 of the bullet being maintained, owing to the hardness of the core. As soon, however, as the bullet begins to enter the flesh or similar tissue, the pits or shallow recesses 9 become filled therewith and with the liquids it contains, with the result that the bullet 95 is rapidly retarded in its progress, such retardation becoming evident even before the body of the bullet, 2, has entered the tissues. This causes a rather violent set back of the core into the body, and this, 100 by reason of the wedge shape of the part 8 of the core, causes the soft metal of the body 2, and the relatively weak material of the jacket, to spread; and these spreading portions catching in the flesh cause the bullet 105 to mushroom, producing a wound of large size, with great incidental shock. The

mushrooming of the body of the bullet frees the core, the shank 5 of which is tapering, and this, being freed, travels forward independently of the mushroomed 5 body of the bullet, penetrating deeply the tissues and acting as an independent arrow or dart. The rapid axial rotation of the core causes a considerable disruption of tissues, due to liquids and particles of tissue 10 entering the pits or recesses of the head 6 and then being violently thrown therefrom by centrifugal force.

In order to facilitate the relative movements between the core and the body 2, 15 which have been described, I prefer to interpose a thin coating 10 of some lubricating material between the contacting surfaces of these two parts. Thus I may cover the stem 5 and tapering part 8 of the core 20 with a thin layer of plumbago paint or coating before the core is set into the recess 4 therefor in the body. This will serve to prevent adhesion of the core and body through corrosion or from other causes, and facilitate 25 the movements which have been described,—the set back of the core and the forward independent flight thereof after the bullet begins to mushroom. I also prefer to coat the exterior of the body with a thin layer 30 11 of plumbago or similar material adapted to serve as a heat insulating layer between the jacket 3 and the body 2 of soft metal. This insulating layer is employed for the purpose of preventing the melting of the 35 outer part of the body by the hot gases of combustion and propulsion with the consequent liability of the bullet becoming slightly deformed by reason of such melting of the metal. But a very thin coating of 40 insulating material is sufficient to afford the protection desired.

The bullet described has many superior features, having great range and flat trajectory, due to the full effect of the powder 45 charge being made available, and the reduced air resistance incident to the recessing of the pointed nose of the bullet; and a full mushrooming effect, combined with deep penetration, due to the separation of 50 body and core of the bullet after the ob-

jective has been struck and penetration of the tissues thereof has taken place. A bullet such as described, therefore, is almost sure to disable an animal struck, by reason of the size of the wound and incident shock 55 produced through the mushrooming of the body of the bullet, and also to cause death by the added effect of deep penetration of the spear or dart that forms the core of the bullet after it separates from the body 60 at the instant the latter mushrooms.

While I have described the several features of my invention as being embodied in a single bullet adapted for sportsmen's uses, it is evident that some of the features 65 thereof are of general application to projectiles of all kinds, particularly the pitting, denting, or recessing of the exterior of the nose of the projectile in order to improve its flight. 70

What I claim is:

1. A projectile having a pointed nose, substantially the entire exposed surface of which is covered with shallow empty pits. 75 2. A bullet having a body of relatively soft metal and a core separate therefrom, the core being shaped with a head constituting the tapering nose of the bullet and with a tapering shank that is seated in said body, there being between the body and the 80 core a lubricating material whereby upon the firing of the cartridge the core sets back slightly expanding the body to cause it to take the rifling of the gun.

3. A mushrooming bullet comprising a 85 body of soft metal, a jacket therefor, and a core having a head that constitutes the exposed nose of the bullet and is exteriorly recessed or pitted, a relatively long tapering stem seated centrally in the soft metal 90 body of the bullet, and a tapering part between the head and stem arranged to serve as a wedge to start a mushrooming action upon impact of the bullet, the core being easily separable from the body of the bullet, 95 upon the mushrooming thereof, whereby it is adapted to travel forward independently as a piercing dart.

CHARLES P. WATSON.
